UNITED STATES PATENT OFFICE

2,528,872

ADJUSTABLE DOMESTIC TOOL CARRIAGE

Wade W. Dick, Shreveport, La.

Application August 27, 1948, Serial No. 46,528

5 Claims. (Cl. 280—43)

1

My invention relates to carriages adapted to support and transport household tools and the like to convenient locations for use by a cleaner or other operator. My invention more specifically relates to an adjustable carriage for holding and transporting a vacuum cleaner together with its various attachments, and furthermore, a carriage wherein one pair of its supporting legs is vertically adjustably mounted in the body of the carriage to adapt the carriage to safely and easily rest on the tread of a stairway.

While the prior art shows vehicles capable of holding vacuum cleaners, as far as I know, no one before my invention has supplied an adjustable vacuum cleaner carriage that is adapted to be adjusted so that it will rest in a safe position on a stairway.

An object of my invention is to provide a carriage wherein an end pair of its supporting wheels is arranged to be turned into and locked in cross-wise directions with respect to the other pair of the carriage's wheels to serve as a brake to prevent forward or reverse movements of the carriage.

Another object of my invention is to provide a carriage, wherein one of the end pair of the wheels supporting the carriage is mounted on a pair of vertically adjustable and rotatably mounted legs of the carriage and wherein the carriage is provided with a clamping mechanism used not only for clamping the adjustable legs of the carriage in vertically adjusted positions to make the carriage sit level when supported by two or more treads of a stairway, but which clamping means is also for use in clamping the legs in turned positions to bring the wheels in crosswise position with respect to the other pair of wheels supporting the carriage to prevent the carriage from rolling down the stairway.

Other objects and advantages of my invention will appear in the course of my general description of the invention describing the embodiment of my invention illustrated in my accompanying drawings.

In general, my invention comprises a carriage provided with a pan-shaped top, which top is provided with a pair of straps for strapping the vacuum cleaner to the top. I also provide the carriage with a pan-like shelf, which shelf is used as a storage space for carrying the attachments of the vacuum cleaner. The rear pair of the legs of the carriage is slidably mounted on the carriage so that the vehicle may be adjusted to sit level when supported by the treads of a stairway. These rear adjustable legs which carry

2

at their bottoms the rear wheels of the carriage, are rotatably mounted in the carriage so that the rear legs and the wheels on their lower ends may be turned crosswise with respect to the front pair of wheels of the carriage. The carriage is also provided with a means for locking these adjustable legs both as to vertically adjusted positions in the body of the carriage and as to their rotated positions in the body of the carriage.

10 In my accompanying drawings I show an embodiment of my invention which I will describe in detail to further explain my invention.

In the drawings:

15 Figure 1 is a perspective view of a vehicle made according to the teachings of my invention, showing it in use holding a vacuum cleaner and parts thereof in its normal position.

Figure 2 is a fractional plan view of the under-side of the left end of the carriage as seen in Figure 1.

20 Figure 3 is a side elevational view of the carriage shown adjusted to sit in an horizontal position on the treads of a stairway.

Figure 4 is a diagrammatic view of the rear end of the carriage illustrating the rear leg adjustment features of my invention.

25 Referring to the drawings, numeral 11 designates the main body portion of my invention in an adjustable domestic tool carriage 10. Numeral 12 designates a pan-shaped top of the carriage body portion 11 which is provided with a pair of adjustable straps 13 for use in strapping down the vacuum cleaner V. The main body portion 11 is also provided with a pan-like shelf 14 positioned directly underneath the top 12 and used for holding various vacuum cleaner attachments. The top 12 and pan-like shelf 14 are joined together by means of four corner angle-shaped spacers 15 which embrace both the top 12 and shelf 14.

30 The carriage 10 is provided with a pair of front supporting legs 16 square in cross section. The front legs 16 are rigidly fastened to the front pair of angle-shaped spacers 15 by means of bolts or other means of fastening. The front supporting legs 16 are made square in cross section to facilitate their assembly into the carriage, but might be made in other shapes if desired. Each of the front supporting legs 16 is provided with an upwardly extending prong 17 near the lower end of the leg which serves as a support for a section of metal tubing T forming parts of the vacuum cleaner's tube extension. Each front supporting leg 16 carries a rotatable castor 18 in its bottom end.

Metal straps 19 are soldered or otherwise fastened to the front angle-shaped spacers 15 through which straps the tube sections T extend when supported by the prongs 17.

The rear supporting legs 20 of my invention in a carriage are vertically, slidably mounted in the main body portion 11 and are also rotatably mounted in the same. The rear supporting legs 20 terminate at their bottoms in bifurcated ends 21 in each of which a rear wheel 22 is rotatably mounted.

The rear supporting legs 20 near their upper ends are provided with aligning stop notches 23 for use with another member of my invention to be described later for locking the rear supporting legs 20 in their fully extended positions as best seen in Figure 1 of the drawings. The rear supporting legs 20 are each provided with a crank handle 24 each of which carries a handle knob 25 for use in turning the crank handle 24 and the rear supporting legs 20 to which the crank handles 24 are rigidly attached. I make the rear supporting legs 20 square in cross section for functional reasons as will be explained later. The rear supporting legs 20 extend through vertically aligned holes, upper holes 26 in the top 12 and lower holes 27 in the shelf 14. Both sets of holes are made large enough for the rear legs 20 to freely slide through them and to be easily rotated in them. Both of the sets of holes, upper holes 26 and lower holes 27, extend through the corners of the top 12 and shelf 14 respectively in order to allow the rear supporting legs 20 to be moved directly in contact with the inner faces of the vertically extending corners defined by the angle-shaped spacers 15.

These angle-shaped spacers 15 serve not only as stops for the rear supporting legs 20 but serve as guides for vertically aligning the rear supporting legs 20 in their vertically adjusted positions in the main body portion 11. The rear supporting legs 20 are clamped against the spacers 15 by means of a spring actuated clamping means 28. Strictly speaking, the clamping means 28 pushes the rear supporting legs 20 into contact with the lower ends of the spacers 15. The upper ends of the rear supporting legs 20 are held close to the upper ends of the spacers 15 by means of surface portions of corners of the top 12 which define the upper holes 26.

The spring actuated clamping means 28 is comprised of a base 29 which is fastened along the under side of an end edge of the shelf 14. A crossbar 30 carrying a pair of presser fingers 31 and a handle 33 terminating in a knob 34 is hinged to the base by means of a pair of spaced spring hinges 35 arranged to urge the presser fingers 31 into gripping contact with flat surfaces of the rear supporting legs 20 with which these presser fingers 31 are aligned. The presser fingers 31 are extended outwardly from the crossbar 30 in parallel curved directions commencing in gradual curves and ending in sharply curved formations 32 which portions of the presser fingers 31 are adapted to fit into locking position in the aligning stop notches 23 when the rear legs 20 are extended full length whether the rear wheels 22 are aligned in lengthwise position of the carriage or in crosswise position.

I use spring hinges 35 which are sufficiently strong to exert enough pressure on flat portions of the rear legs 20 to maintain the rear legs in proper vertically adjusted positions supporting the load of a vacuum cleaner V and parts of same such as shown in Figure 3; wherein the

rear legs 20 are raised up to rest on an elevated tread of the stairway S.

In adjusting the carriage 10 for positioning on a stairway S, the operator should hold the handle H of the vacuum cleaner strapped to the carriage to support the carriage 10 and the vacuum cleaner V while he depresses the handle 33 of the clamping means 28 to release the rear legs 20. After the rear legs 20 have assumed their proper vertical positions in bringing the carriage 10 into a horizontal position, the operator releases the handle 33 allowing the spring hinges 35 to again urge the presser fingers 31 into contact with the flat faces of the rear legs 20. The next thing the operator does is to turn the crank handles 24 to the left or to the right to force the rear legs 20 into positions, against the pressure of the spring hinges 35, to align the rear wheels 22 into crosswise non-rolling position as best seen in Figure 3 to prevent the carriage 10 from rolling down the stairway S. On some occasions it might be desirable to turn the rear wheels 22 as shown in Figure 3 to prevent the carriage 10 from being moved forward and backward in its normal position with the rear legs 20 fully extended.

My invention in a carriage 10 may be made out of any suitable material such as woods, plastics or metal. I have found sheet metal to be a very desirable material out of which to fabricate most of the carriage. The adjustable straps 13 should preferably be made out of a leather material or some fabric.

Various changes in the construction illustrated in my drawings may be resorted to within the scope of my subjoined claims.

Having thus described my invention, I claim:

1. A domestic tool carriage comprising an elongated body portion including a top surface, a pair of parallel spaced legs rigidly secured to said body portion, depending from said body portion adjacent an end of the same in the lower ends of which legs castors are rotatably mounted, a second pair of parallel spaced legs slidably and rotatably mounted in said body portion adjacent the opposite end of said body portion, each of which legs is provided with a pair of longitudinally extending flat surface portions lying in right-angularly intersecting planes, each of said second mentioned legs terminating in a bifurcated end in which a wheel is rotatably mounted, a spring actuated clamping means provided with presser fingers adapted to contact said flat surfaces of said second mentioned legs to frictionally hold said legs in rotated positions in said body portion, whereby said carriage may be rested in a horizontal position on separate treads of a stairway or the like and whereby said second mentioned legs may be rotated and held in positions to align said wheels carried by the same into crosswise position with respect to the length of said carriage.

2. The carriage as claimed in claim 1, wherein each of said second mentioned legs is provided with a peripherally extending groove in which said presser fingers are adapted to sit to lock said second mentioned legs in their fully extended positions.

3. The carriage as claimed in claim 1, wherein each of said second mentioned legs is provided with a peripherally extending groove in which said presser fingers are adapted to sit to lock said second mentioned legs in their fully extended positions and wherein each of said second mentioned legs is provided with a crank

handle for turning the same in opposition to the pressure exerted on second mentioned legs by said spring actuated clamping means.

4. The carriage as claimed in claim 1, wherein said top surface is made pan-shaped and is provided with an adjustable strap adapted to secure a vacuum cleaner or the like on said top.

5. The carriage as claimed in claim 1, wherein said top surface is made pan-shaped and is provided with an adjustable strap adapted to secure a vacuum cleaner on said top surface and wherein said body portion includes a pan-shaped shelf positioned beneath said top surface adapted to hold vacuum cleaner parts and attachments and wherein said first mentioned legs

are provided with upwardly extending prongs adapted to support tubular hose extensions of a vacuum cleaner.
